CLAIM

The ornamental design for an ice cream cone cup, as shown and described.

DESCRIPTION

FIG. 1 is a perspective view of the ice cream cone cup of the present invention with the tabs spread;

FIG. 2 is a top plan view thereof;

FIG. 3 is a bottom plan view thereof; and,

FIG. 4 is a side elevational view, the opposite side being identical.

The broken line showing of ice cream in an ice cream cone is for illustrative purposes only and forms no part of the claimed design.
